UNITED STATES PATENT OFFICE.

ADOLPH POTDEVIN, OF BROOKLYN, NEW YORK, ASSIGNOR TO POTDEVIN MACHINE COMPANY, OF NEW YORK, N. Y., A CORPORATION OF NEW YORK.

MACHINE FOR COATING CARDBOARD AND OTHER MATERIALS.

Application filed July 28, 1921. Serial No. 488,158.

To all whom it may concern:

Be it known that I, ADOLPH POTDEVIN, a citizen of the United States, and resident of the city of New York, borough of Brooklyn, in the county of Kings and State of New York, have invented certain new and useful Improvements in Machines for Coating Cardboard and Other Materials, of which the following is a specification.

This invention relates to machines for applying coating in a liquid state to the surface of cardboard and other materials; having reference more especially to that class of machines wherein a roll or drum is mounted to rotate within and above a tank containing the coating liquid, the peripheral surface of such roll or drum being partly immersed in the contents of the tank and being adapted in its rotation to transfer the liquid in a film or layer to an opposing surface.

An object of my invention is to provide a simple and efficient construction whereby a smooth and uniform application of the liquid to the cardboard or other material is effected.

Another object is to provide means whereby the liquid contents of the tank are kept constantly in circulation in such a manner as to insure a substantially even level as well as the uniform viscosity of the liquid within the tank preparatory to the removal of the liquid by the rotating roll.

With these objects in view my invention comprises novel features of construction and combinations of parts which will be herein-after described and claimed.

In the drawings—

Figure 1 is an end elevation of a coating machine to which my invention is applied, said machine being illustrated as one for coating cardboard with glue.

Fig. 2 is a transverse vertical section of the machine, indicating the circulation of the liquid contents of the tank.

Fig. 3 is a longitudinal vertical section of the machine on the line 3—3 of Fig. 2.

Fig. 4 is a section similar to Fig. 2, but showing a modified form of the diverter.

Referring to the drawings, 5 designates an elongated tank adapted to contain glue or other liquid coating substance; and 6 designates a transfer roll which is journaled in bearings in the ends of the tank in such

a manner that the surface of the roll is 55 partly immersed in the liquid and is adapted in its rotation to raise the liquid and apply it to the surface of the material to be coated.

7 designates a feed and pressure roll 60 which is maintained yieldingly upon the sheet of material, as A, imposed on the transfer roll. In the present instance the roll 7 is carried by a pair of pivoted arms 8 which are arranged at the ends of the tank 65 and have their free ends connected to retracting springs 9. Set-screws 9' fitted in the arms and contacting with the ends of the tank provide means for vertically adjusting the arms and the roll 7. 70

10 designates a doctor roll adapted to distribute and regulate the thickness of the liquid on the surface of the roll 6. This roll is illustrated as carried by a pair of upstanding rock-arms 11 which are pivoted 75 on the respective ends of the tank; a set-screw 12 in the adjacent side wall of the tank being provided to effect minute adjustment of the roll 10 in respect to the surface of the roll 6. 80

The shaft of the roll 6 is provided with a spur wheel 13 which meshes with a pinion 14 loose on an adjacent stud shaft 15 extending from one end of the tank, and with a pinion 16 fast on the shaft of the roll 10. 85 Fast on the pinion 14 is a pulley 17 and also fast on the shaft of the pressure roll 7 is a pulley 18. About these pulleys is flexed a belt 19 which is driven from a suitable source of power. Thus motion is directly 90 transmitted by the belt to the pulleys 17, 18; the rolls 6, 10 are driven through the gearing from the pulley 17, and the pressure roll 7 partakes of the rotation of the pulley 18. The ratio of the gearing is such that the 95 surface speed of the pressure roll exceeds that of the transfer roll 6. When the transfer and pressure rolls, and, in consequence, the interposed sheet, are driven at the same surface speed the film of liquid carried up 100 by the transfer roll has a tendency to drag and spread rearwardly upon the under surface of the sheet, particularly when glue is being applied to material of relatively heavy texture; but by increasing the speed of the 105 pressure roll above that of the transfer roll as above mentioned, the movement of the sheet is correspondingly accelerated, and

the objection indicated is effectually overcome, thus insuring a smooth and uniform application of the glue to the sheet.

The feed and pressure roll is preferably covered with rubber, or the like, or is knurled, in order to ensure a good frictional contact with the sheet of material under treatment. Other means than the roll 7 may be employed to advance the sheet of material at a greater surface speed than the transfer roll.

When a coating substance of high viscosity or of heavy body is used, the transfer roll, in its rotation, tends to advance and pile up the substance in the front or doctor roll end of the tank; such substance in some cases overflowing the tank. To obviate this objection and also to maintain the uniform viscosity of the liquid, a diverting member 20 is positioned slightly below and parallel with the lower peripheral surface of the roll 6, as seen in Fig. 3. This member is so constructed and arranged as to provide a narrow space between the diverter and the lower surface of the roll and a relatively wide space between the diverter and the bottom of the tank, as illustrated. The body of liquid contiguous to the lower surface of the rotating roll 6 is carried thereby through the longitudinal space between such surface and the diverter, and an upper current toward the rear wall of the tank is thus established, which current is thence directed downwardly and caused to flow in a return path through the space below the diverter; whereupon the lower current is directed upwardly and toward the surface of the transfer roll, and so on. This circulation of the liquid continues during the rotation of the transfer roll, and hence a substantially even level as well as uniform consistency of the liquid within the tank is maintained.

In Figs. 2 and 3 I have illustrated the diverter 20 in the form of a horizontal flat 45 metallic strip, and in Fig. 4 I have indicated the strip as forwardly and upwardly extended and curved.

I do not limit my invention to the particular type of machine illustrated, nor to the specific details of construction herein disclosed, as the mechanism may be applied to various forms of coating machines and may be modified within the principle of the invention and the scope of the appended claims.

I claim—

1. In a coating machine, the combination of a tank for liquid coating material, a roll mounted to rotate in the contents of the tank, and a member interposed between the bottom of the tank and the lower surface of the roll and constructed and arranged to provide a relatively narrow space between said member and the roll, and a relatively wide space between said member and the bottom of the tank.

2. In a coating machine, the combination of a tank for liquid coating material, a roll mounted to rotate in the contents of the tank, and a stationary diverter extending longitudinally of and in spaced relation to the path of rotation of the immersed surface of the roll.

3. In a coating machine, the combination of a tank for liquid coating material, a roll mounted to rotate in the contents of the tank, a relatively thin horizontal strip extending longitudinally of and in spaced relation to the path of rotation of the lower surface of the roll to provide upper and lower circulation spaces for the liquid.

Signed at Brooklyn, in the State of New York, this 16th day of July, A. D. 1921.

ADOLPH POTDEVIN.
